ARNOLD EGLI, OF PLAUE, GERMANY, ASSIGNOR TO VOGTLÄNDISCHE MASCHINEN-FABRIK (VORMALS J. C. & H. DIETRICH) ACTIENGESELLSCHAFT, OF PLAUE, GERMANY.

MATRIX FOR STEREOTYPE-PLATE MOLDS.

1,026,739.

Specification of Letters Patent.

Patented May 21, 1912.

Application filed November 10, 1909. Serial No. 527,235.

To all whom it may concern:

Be it known that I, ARNOLD EGLI, a subject of the King of Prussia, residing at Plauen, in Vogtland, in the Kingdom of 5 Saxony and German Empire, have invented new and useful Improvements in Matrices for Stereotype-Plate Molds, of which the following is a specification.

The subject of my invention is a matrix 10 for the molds employed in casting stereotype-plates.

According to my invention the matrix presents not only the usual marginal elevation for damming or restraining the liquid 15 metal, but is also provided along its top edge (which during the casting process is located directly at the "gate," or place where the molten metal is run in) with one or more additional elevations or protruding 20 portions of any suitable shape. The purpose of these auxiliary protrusions is to accommodate the depressions due to shrinkage which depressions occur on the "setting" or solidifying of the plate. The ele- 25 vation ordinarily provided around the edge of the matrix for the purpose of restraining the molten metal exerts no influence upon the depressions occurring on the setting of the cast plate, since said elevation is lo- 30 cated too close to the text. It is only the marginal elevations, located beyond the said elevation which confines the printing-surface of the plate, that are able to accommodate the requisite quantity of still uncon- 35 sealed feeder-metal for supplying the de- pressions.

A practical embodiment of my invention is illustrated in the accompanying drawing, in which—

40 Figure 1 is a plan of the matrix, and Fig. 2 a section on the line A—A of Fig. 1. Fig. 3 is a sectional view, showing the matrix in the mold.

The matrix *e* which is placed in the mold 45 *c, d* for the stereotype-plate, consists of stout paper, having the composition stamped or

pressed into it, and provided with the usual marginal rib or protrusion *a*, adapted to confine the text or impressed composition. This rib, or elevation *a*, however, acts solely 50 to dam or restrain the molten metal in the casting operation. For, despite the elevation, it frequently occurs in casting that on the setting of the cast plate, the depressions due to shrinkage form directly in the elevation 55 *a* and even in the printing-surface, that is, the text of the plate, whereby the cast stereotype-plate is rendered of course useless. According to my invention the depressions which occur on the setting of the 60 plate are caused to form with certainty entirely outside of the actual printing-surface. This effect is obtained by the matrix being furnished beyond the usual elevation which confines the text, or printing- 65 surface, with other raised parts or protrusions *b*, along its top edge, *i. e.*, at the place where the metal is poured in. These supplementary elevations accommodate the de- 70 pressions. They may be of course of any 70 suitable shape and may be if desired connected with each other at certain places by cross members.

When the hot metal is poured into the mold *c, d*, at *f* in Fig. 3, part of the metal 75 will run into the grooves formed by the elevations *a, b*. As the plate begins to shrink, liquid metal will be sucked away at *a'* (Fig. 3). The depression caused there- 80 by is, however, filled up again with the hot 85 liquid metal that has been dammed up by the elevation *b*. The matrix *e* being made of paper, which is a poor conductor of heat, the hot metal around the elevations will keep liquid a longer time than the metal 85 forming the plate, hence there is always a sufficient quantity of liquid metal to fill the depressions occurring through shrinkage, while the plate solidifies.

The advantage of my invention lies in the 90 fact that at the first casting operation, always a perfect printing surface is ob-

tained, since every operation is successful. The process of casting stereotype plates is thereby, of course, greatly expedited.

Having thus described my invention, I declare that what I claim as new and desire to secure by Letters Patent is:—

A matrix for molds for casting stereotype-plates, provided with the usual elevation for restraining the liquid metal and a number of supplementary elevations, situ-

ated beyond said elevation and adapted to accommodate any depressions due to shrinkage of the metal within said elevation.

In testimony whereof I have signed my name to this specification in the presence of two subscribing witnesses.

ARNOLD EGLI.
